SIGNALING SYSTEM FOR RAILROADS

Andrew Langdon, Rochester, N. Y., assignor to
General Railway Signal Company, Rochester,
N. Y.

Application June 23, 1932, Serial No. 618,922

11 Claims. (Cl. 246—3)

This invention relates to railway signaling, and more particularly to a check lock circuit for assuring safe interlocking between the signals governing the entrance of traffic at opposite ends of 5 a single track section.

Sometimes it happens that two interlocking plants are located only a short distance apart, and that these interlocking plants are connected by several single tracks, each of which normally 10 allows traffic to move in a particular direction, but wherein it may be necessary to reverse the direction of traffic in such section due to congestion, repairs being made on other tracks, or the like. Suitable interlocking means must of course be 15 provided to prevent traffic being set up in both directions on said single track, check lock or traffic section at one time, and means must be provided for preventing changing the direction of traffic with a train in or approaching the traffic section, 20 unless proper safeguards are introduced.

In accordance with the present invention it is proposed to employ two relays in series, one located at each of the entering ends to such single track section, preferably called lever repeating 25 relays, and to employ a second circuit, preferably called a direction circuit, for checking whether or not these two lever repeating relays are in corresponding positions, and to allow traffic to be set up in one direction when these two lever repeating relays are energized and to be set up in the opposite direction when these two relays are deenergized, the checking circuit being employed 30 to assure against conflicting signal indications being given as might otherwise occur if energy 35 were accidentally applied to an intermediate point of the circuit including the two relays in series, for under this condition one of these relays could be energized and the other remain deenergized. The checking circuit referred to is also 40 employed as a means for selecting between affiliated signal controlling circuits to enable a reduction in the line wire requirements between the two ends of the check lock section, this being one of the primary purposes for controlling non-automatic or call-on signals.

Other objects, purposes and characteristic features of the present invention reside in the provision of suitable time measuring safety means to prevent sudden changes in the direction of 50 traffic being set up, which might endanger a fast moving train approaching either in such section or in an approach section.

Other objects, purposes and characteristic features of the present invention will in part be obvious from the accompanying drawings and will in part be more specifically pointed out herein-after.

In describing the invention in detail reference may be had to the accompanying drawings, in 60 which:—

Fig. 1 shows a check lock circuit embodying the present invention for controlling non-automatic call-on signals; and

Fig. 2 illustrates one manner in which automatic signals may be superimposed on the system shown in Fig. 1 to advantage, so that one pair of line wires suffices to control the home and distant indications of two opposing signals associated with the check lock section.

Structure of Fig. 1

Referring to Fig. 1 of the drawings, the track rails 5 have been shown divided into track sections by insulating joints 6, one section of which constitutes the single track section to which the 15 check lock circuit of the present invention has been shown applied. It is of course understood that suitable switches and crossovers will be employed beyond the extremities of the single track section in question, these track switches, crossovers, and the like (not shown), constituting the 20 interlocking plants located at opposite ends of this check lock section. The check lock section in question is provided with the usual track circuit including the track relay T and the track battery 25 7. The normal direction of traffic in this single track section is preferably from left to right, or west to east, as indicated by the arrow.

At the east end of the single track section has been shown a non-automatic or call-on signal 1C 30 for controlling the movement of traffic into said section from that end, a similar call-on signal 2C being shown at the west end thereof. In the approach section to these signals 1C and 2C have been shown track relays T¹ and T² being 35 repeated by approach stick relays AS¹ and AS² respectively, these approach stick relays having associated therewith suitable timing devices such as thermal relays TR¹ and TR² respectively.

At the west end of the single track section has 40 been shown an operator's tower OT, in which there is a lever L for setting up a particular direction of traffic over the single track section. This controlling office may be located at a considerable distance from the check lock section, 45 without sacrifice of safety, even though only one line wire and common are employed between the operator's tower and the rear end of the check lock section. When this lever L is moved to its abnormal position it energizes a circuit including 50 the lever repeating relays DR¹ and DR² connected in series, the relay DR¹ being located near the signal 1C and the relay DR² being located near the signal 2C. In order to assure that no conflicting signal indications can be given, as for 55 instance might otherwise be true if the line wire 10 were accidentally connected to an unauthorized source, the direction relays DC¹ and DC² have been provided. As is obvious from the drawings one of these relays DC¹ or DC², depending 60

- on whether the relays DR^1 and DR^2 are energized or deenergized, is energized through a circuit including the contacts of relays DR^1 and DR^2 assuming corresponding positions. For instance, the relay DC^1 is shown in its energized condition and is energized through back contacts of the relays DR^1 and DR^2 in series. This energizing circuit may be traced as follows:— beginning at the terminal (+) of a suitable source of current, front contact 9 of relay DC^1 , wire 11, polar contact 12 of this same relay, wire 13, back contact 14 of the relay DR^1 , wires 15, 16 and 17, back contact 18 of the relay DR^2 , wire 19, winding of the relay DO^2 , wire 20, back contact 21 of relay DR^2 , wires 22, 23 and 24, back contact 25 of the relay DR^1 , wire 26, polar contact 27 of the direction check relay DC^1 , wire 28, neutral contact 29 of the relay DC^1 and to the other terminal (—) of said source.
- 20 The track relay T is also repeated through a track stick relay TS , the pick-up circuit for which may be traced as follows:— beginning at the terminal (+) of a suitable battery, front contact 30 of the direction relay DC^2 , wire 31, polar contact 32 of this same relay, wire 33, back contact 34 of the relay DR^2 , wires 35 and 36, front contact 37 of the track relay T , wires 38 and 39, through the winding of the relay TS and to the other terminal (—) of said battery.
- 30 It will be noted that the relay TS remains up even though the track relay T drops, this through current flowing in the following stick circuit:— beginning at the terminal (+) of said battery, front contact 30 of the relay DC^2 , wire 31, polar contact 32 of this same relay, wire 33, back contact 34 of the relay DR^2 , wires 35 and 40, heating coil 41 of the relay TR , wire 42, stick contact 43 of the relay TS , wires 44 and 39, winding of the relay TS to the other terminal (—) of said battery. It will be noted that the stick circuit just traced includes the correspondence contacts 32 and 34 of relay DC^2 and DR^2 , respectively.

From this stick circuit it is apparent that if a direction of traffic is changed while the track relay T is deenergized the track repeater stick relay TS will also be deenergized, and that this relay TS may only be picked up after an interval of time if the track relay T remains deenergized, this through the medium of the contact 45 of the thermal relay TR . It may be pointed out here, that the flow of current in the heating coil 41 results in closure of the contact 45 shunting the contact 37, but that with the relay TS picked up and stuck up the closure of its contact 50 will be of no avail until the thermal relay has been fully cooled under which condition its contact 52 is reclosed. Any other suitable time element device may be employed in lieu of a thermal relay if desired, or this protection may, if desired, be omitted. Also, it will be noted that the call-on signal 2C cannot be energized and cleared unless the thermal relay TR is in its normal condition, thus requiring this relay TR to return to normal temperature, or at least to its ultimate temperature with the relay TS included in series with its heating coil 41, before it can be called upon for a second operation.

The circuit for clearing the call-on signal 2C may be traced as follows:— beginning at the terminal (+) of said battery, front contact 50 of the relay TS , wire 51, back contact 52 closed only if the thermal relay TR is in its normal cooled condition, wire 53, front contact 54 of the relay DC^2 , wire 55, polar contact 56 of this same

relay, wire 57, signal mechanism of the call-on signal 2C and to the other terminal (—).

The direction relay DC^1 is normally energized through the following circuit:— beginning at the terminal (+) of a suitable battery, back contact 60 of the thermal relay TR^1 , wire 61, front contact 62 of the approach stick relay AS^1 , wire 63, back contact 64 of the relay DR^1 , wire 65, winding of the relay DC^1 , wire 66, back contact 67 of the relay DR^1 and to the other terminal (—) of said battery. The purpose of the thermal relays TR^1 and TR^2 is the same as that of the thermal relay TR , namely to cause a retarded pick-up of a stick relay, followed by another period of delay necessary to allow cooling of this thermal relay before completion of a second circuit.

Operation of Fig. 1

It will be noted that the call-on signal 2C is in the call-on position whereas the call-on signal 1C is at stop, so that traffic may move in the normal direction as indicated by the arrow. Let us now assume that the operator in the tower OT moves his lever to the reverse position, this in order to set up west-bound traffic on the single track section. This movement of the lever L will energize the direction relays DR^1 and DR^2 , thereby breaking the energizing circuits for the relays DC^1 and DC^2 , heretofore traced.

Picking up of the relay DR^2 will by its lifting of the contact 34 destroy the condition of correspondence between the contacts 32 and 34 of relays DC^2 and DR^2 , so the relay TS will be deenergized, but since the relay DC^2 is operated to its reverse polarity position, after the period of time required for the signal 2C to assume the stop position to close its contact 8 to complete the pick-up circuit for relay AS^2 , the correspondence between the contacts 32 and 34 is re-established and if the relay T is in its energized condition the relay TS is again picked up without the intervening operation of the thermal relay TR . The relay AS^2 if once up is of course stuck up through its stick contact 88. Also if relay T^2 is down, relay AS^2 will not be picked up until the thermal relay TR^2 has been energized and closed its front contact.

Picking up of the relay DR^2 will thus result in immediate energization of the direction relay DC^2 with current of reverse polarity through the following circuit:— beginning at the terminal (+), back contact 70 of the thermal relay TR^2 , wire 71, front contact 72 of the approach stick relay AS^2 , wire 73, front contact 21 of relay DR^2 , wire 20, winding of the relay DC^2 , wire 19, front contact 18 of the relay DR^2 and to the other terminal (—). It should be noted that the direction of current flow through the direction relay DC^2 has now been reversed, so that its polar contacts assume the left-hand dotted position, as a result of which the circuit for the call-on signal 2C is broken at the polar contact 56 of the relay DC^2 in addition to the break previously made at the contact 50 of relay TS .

With the lever repeating relays DR^1 and DR^2 now both energized and with the direction relay DC^2 assuming its left-hand polar position, the direction relay DC^1 is energized through the following circuit:— beginning at the terminal (+), front contact 50 of the track stick relay TS , wire 51, back contact 52 of the thermal relay TR , wire 53, front contact 54 of the relay DC^2 , wire 55, polar contact 56 of this relay assuming its left-hand position, wire 57, front contact 76 of the

relay DR², wires 77, 16 and 78, front contact 64 of relay DR¹, wire 65, winding of relay DC¹, wire 66, front contact 67 of relay DR¹, wires 68, 23 and 69, front contact 79 of relay DR², wire 80, polar 5 contact 81 of relay DC², wire 82, front contact 83 of relay DC² and to the other terminal (-).

It is thus seen that the relays DR¹ and DR² must assume corresponding positions in order to energize the direction relay at one end of the 10 single track section, and furthermore, that the polar direction relay at the other end of this section must be energized to the proper polar position. Analyzing the various checks from a slightly different angle, it should be noted by referring to Fig. 1, that energization of the relay DR² or DR¹, for any reason, will result in deenergization of the relay DC², this because its energizing circuit includes back contacts of both of the relays DR¹ and DR², and that with relay DC² deenergized the call-on signal 2C cannot be set 15 in the call-on position. Furthermore, in order to energize the call-on signal 1C at the other end of the single track section requires its associated relay DC¹ to assume a polar position, which it can only obtain by current flowing over the 20 line wires 16 and 23, and then only if the relays DR¹ and DR² are both energized and the relay DC² assumes the proper polar position, so that 25 there are numerous checks which must be satisfied before the call-on signal 1C can be placed in its proceed position if the system formerly assumed the normal position, and similarly, if 30 the direction of traffic has once been reversed, numerous checks must be satisfied before normal direction of traffic can be set up by the 35 other of the signals 1C or 2C.

Structure of Fig. 2

Fig. 2 shows conventionally the same apparatus as shown in Fig. 1 (many parts thereof having been omitted for convenience), but in addition to this apparatus shows how the main semi-automatic signals 1 and 2 associated respectively with the call-on signals 1C and 2C may be controlled. 40 Since the system shown in Fig. 1 affords two polar relays DC¹ and DC² always assuming when energized corresponding polar positions, this feature may be taken advantage of for transmitting favorable indications both caution and clear to the 45 semi-automatic three-position signals 1 or 2, one at a time, in accordance with the direction of travel permitted at that time. In other words, the line wires 90 and 91 may at one time be employed to control the home relay 2H for governing 50 the signal 2, as is normally the case in Fig. 2 of the drawings, but with the polar relays DC¹ and DC² reversed the same line wires 90 and 91 may be used to control the home relay 1H for 55 governing the signal 1.

60 It will be noted that the polarity of energization of the home-relay 2H is reversed by dropping of track relay T¹ through the medium of contacts 86 and 87 of track relay T¹, thereby placing the signal 2 in its caution position signifying that the second block in advance is occupied. 65 Also, it should be noted that dropping of the track relay T, through the medium of its contacts 92 and 93, will result in deenergization of the home relay 2H, thereby placing the signal 2 in the stop position manifesting that the block immediately 70 in advance of the signal 2 is occupied. Similarly, if the relays DC¹ and DC² assume the left-hand polar position, signifying west-bound traffic, the home relay 1H is controlled to a polar position 75 depending upon the position of contacts 94 and

95 of the track relay T², but relay 1H is deenergized if the track relay T is deenergized, this for reasons already explained. In other words, both of the relays DC¹ and DC² must have their neutral contacts 96, 97, 98 and 99 closed, before a 5 home relay 1H or 2H can be energized, and their polar contacts 100, 101, 102 and 103 must assume corresponding positions before either of these 10 home relays 1H and 2H can be energized, and these home relays 1H and 2H are furthermore controlled by the track relay of the block next in advance and the track relay of the second block in advance of the signal controlled by such home relay.

In the arrangement shown in Fig. 2 the call-on 15 signals 1C and 2C are controlled in exactly the same way as they are in the arrangement shown in Fig. 1 of the drawings, except that their associated semi-automatic signal 1 or 2 must assume the stop position before such call-on signal can assume 20 its call-on position. This requisite is carried out by the provision of the semaphore contact 57¹ operated by the signal 2 in the control circuit for the call-on signal 2C, a similar contact 59 being 25 included in the circuit for the call-on signal 1C.

It may be pointed out that (see Fig. 1) the approach stick relay AS² can only be energized if the non-automatic signal 2C is at stop and if once deenergized cannot be picked up by placing the signal 2C to stop until after a period of delay necessitated by the thermal relay included in its pick-up circuit, but that this delay is cancelled if there is no train in the approach section to the signal 2C due to the shunt afforded by the front contact 85 of the track relay T². What has been 35 said about the relay AS² is also true of the relay AS¹ with respect to its associated apparatus. Referring, however, to Fig. 2 it will be noted that the heating coil of the thermal relay TR² includes the 40 semaphore contact 8 of signal 2C and contact 81²⁰ of signal 2 in series, so that both of these signals must be at stop to afford a heating circuit for this thermal relay. What has been said about signals 2 and 2C and their associated thermal relay is also true of signals 1 and 1C and their 45 associated relay (not shown in Fig. 2).

It should be noted that the semi-automatic signals 1 and 2 are controlled in the usual way by the home-and-distant relays 1H and 2H respectively, the caution and clear wires being designated *ca* and *cl*, respectively. For the signal 2, for instance, the caution wire *ca* or the clear wire *cl* is selected by the polar contact 105, and neither of these wires can have current applied thereto unless the neutral contact 106 of relay 2H is closed. 55

Having thus shown a check lock circuit for a particular purpose, this check lock circuit, including numerous checks which must be satisfied before the function which is to be performed can be carried out, and the invention having been shown 60 applied to a particular problem, it is to be understood that the underlying checking features disclosed herein may be applied to other problems encountered in railway signaling, and that modifications and additions may be made to adapt the 65 present invention to the particular problem encountered in practicing the same, all without departing from the spirit or scope of the invention, except as demanded by the scope of the following 70 claims.

What I claim as new is:—

1. In combination, a track section, a signal at each end of said section and governing the entrance of trains into that end of said section, a neutral relay associated with each of said signals, 75

- a manually controlled circuit for at times energizing said relays in series, a signal control relay associated with one of said signals for controlling that signal, and a circuit, including front contacts of each of said neutral relays, for energizing said signal control relay, said circuit being governed by traffic conditions in approach to said other signal. 5
2. In combination, a track section, a signal at each end of said section and governing the entrance of trains into that end of said section, a neutral relay associated with each of said signals, a manually controlled circuit for at times energizing said relays in series, a signal control relay associated with one of said signals for controlling that signal, and a circuit for said signal control relay, said circuit being governed by said other signal and traffic conditions in approach thereto and including front contacts of said neutral relays. 10
3. In combination, a track section, a signal at each end of said section and governing the entrance of trains into that end of said section, a neutral relay associated with each of said signals, a manually controlled circuit for at times energizing said relays in series, a signal control relay associated with one of said signals for controlling that signal, a circuit for said signal control relay including front contacts of said neutral relays, and means allowing closure of said circuit following the putting to stop of said other signal only after said other signal has been put to stop a predetermined time if a train is in approach thereto. 15
4. In a railway signal system, the combination with a single track section, a signal at each end of said section and governing the entrance of trains into that end of said section, a neutral relay associated with each of said signals, a circuit for at times energizing said relays, a second relay associated with each of said signals, and wires extending along said section for energizing one or the other of said second relays depending upon whether the contacts of said two first mentioned relays are in picked up or retracted positions. 20
5. In a railway signal system, the combination with a single track section, a signal at each end of said section and governing the entrance of trains into that end of said section, a neutral relay associated with each of said signals, a circuit for at times energizing said relays, a polar relay associated with each of said signals, and circuit wires extending along said section for energizing one or the other of said polar relays in accordance with the energized or deenergized condition of said two first mentioned relays. 25
6. In a railway signal system, the combination with a single track section, a signal at each end of said section and governing the entrance of trains into that end of said section, a neutral relay associated with each of said signals, a circuit for energizing said relays, a second circuit including a relay controlled through front contacts of said first mentioned two relays for clearing one of said signals, and a time controlled contact for allowing control of said other of said signals, only after said second circuit has been opened for a predetermined time. 30
7. In a railway signal system, the combination with a single track section, a signal at each end of said section and governing the entrance of trains into that end of said section, a neutral relay associated with each of said signals, a circuit for at times energizing said relays, a second relay associated with one of said signals for controlling that signal, a circuit for said signal control relay including front contacts of said neutral relays, and means allowing closure of said circuit following the putting to stop of said other signal only after said other signal has been put to stop a predetermined time if there is a train in said track section. 35
